UNITED STATES PATENT OFFICE.

WILLIAM E. BURNETT, OF NEWARK, NEW JERSEY.

PHOTOGRAPHIC-PRINTING FRAME.

SPECIFICATION forming part of Letters Patent No. 762,228, dated June 7, 1904

Application filed July 29, 1903. Renewed May 18, 1904. Serial No. 208,522. (No model.)

To all whom it may concern:

Be it known that I, WILLIAM E. BURNETT, a citizen of the United States, residing at Newark, in the county of Essex and State of New Jersey, have invented and produced new and original Improvements in Photographic-Printing Frames; and I do hereby declare the following to be a full, clear, and exact description of the invention, such as will enable others skilled in the art to which it appertains to make and use the same, reference being had to the accompanying drawings, and to numerals of reference marked thereon, which form a part of this specification.

The objects of this invention are to facilitate the work of examining a photographic print as the same is being subjected to actinic rays of the sun or other light in connection with a suitable negative, to quicken the work of "loading" or inserting the negative and sensitive paper in the frame, to reduce the liability of displacing the paper during the printing process, to reduce the liability of the negative dropping out of the frame when changing the paper, and to secure other advantages and results, some of which may be referred to hereinafter in connection with the description of the working parts.

The invention consists in the improved photographic-printing frame and in the arrangements and combinations of parts of the same, all substantially as will be hereinafter set forth and finally embraced in the clauses of the claim.

Referring to the accompanying drawings, in which like numerals of reference indicate corresponding parts in each of the several figures, Figure 1 is a plan of the back of my improved printing-frame. Fig. 2 is a section of the same on line *x*, a certain sectional back plate being removed therefrom. Fig. 3 is a sectional view of the said back plate on the same line *x*. Fig. 4 is a detail section of the body portion of the frame, taken on an enlarged scale at line *y*, Fig. 1. Fig. 5 is a side view of the body portion of said frame partly broken away. Fig. 6 is an end view of the frame. Fig. 7 is a plan of one end of the body portion, showing certain catching devices; and Fig. 8

is a plan of a part of a hinged section of said frame.

In said drawings, 10 indicates the body portion of the frame, which is preferably of pieces of wood suitably joined together in oblong rectangular form and open at the center to permit passage of the light to the sensitive paper lying back of the negative arranged therein.

11 indicates a seat for the negative formed at the inner side of the body of the frame near the front thereof. Near one end of the body portion of the frame the same is thicker or is raised above the opposite end, as at 12, the said raised part being beveled, as at 13, where the said body portion of the frame is provided with hinge connections for a hinged frame-section 14, which is of a thickness about equal to the difference between the thickness of the low and elevated parts of the frame-body 10, so that when said hinged section 14 lies against said low part of the frame-body it will effect a uniform thickness of the frame at both ends. The hinged ends 141 of the hinged section of the frame are beveled, as shown at 15, so that the hinged section can turn on its hinge-pin 16, Figs. 5, 7, a limited distance sufficient to permit the operator to observe the condition of the photographic print, as hereinafter described. At the opposite longitudinal sides of the frame are secured flat resilient metal pieces 17, preferably as wide as the thicker part of the frame-body, which are rigidly fastened to the said frame-body at its elevated part; but at the thin end of the frame opposite said elevated part said resilient pieces are free to move laterally away from the body and serve as spring-catches to hold the hinged section closed. Said spring-catches are perforated, as at 18, to receive the pins 19 on the opposite sides of the hinged sections 14. The relation of the pins 19 and perforations 18 may be changed, as is obvious. The metal pieces 17 are also perforated where rigidly fixed to the body portion of the frame, as shown in Fig. 5, to receive the hinge-pins 16. Said hinge-pins 16 are stationed on the line where the oppositely-inclined planes of the bevels 13 15 intersect and are preferably fixed on plates

20, fastened to the sides of the hinged section 14, as shown in Figs. 5 and 8.

To release the hinged section 14, held in its closed position by the catching means 17 19, 5 I have provided the construction shown in Figs. 5, 6, and 7, where the body 10 of the frame is grooved from side to side at its thin end. A wedge rod or plate 21 fits the groove, so as to slide inward therein away from the 10 end of said frame, such sliding being effected by pressure of the thumb on the outer edge of said wedge-rod at the finger-recesses 22 22, formed in the outer side or edge of the thin end of the frame. The oppositely-beveled 15 ends of the rod 21 impinge on the pins 23, Fig. 7, fastened to the spring-metal pieces 17 and inwardly extending to a position to be engaged by said rod, thus engaging, when the wedge-rod is pressed inward, the pins 23, and 20 the resilient pieces 17, to which they are fastened, will be pressed outward, as will be obvious, and this action will throw the perforated ends of said pieces 17 away from the short pins 19 to effect the desired release. 25 Thus released the hinged section 14, attached to the frame-body, is thrown at its free end upward or away from said body by springs 25, seated on a shoulder 26, formed at the inner side of said body and held thereon by 30 screws 27 or otherwise. The free ends of the springs cross the hinge-joints and press upward on the pins 28 of the hinge-section 14 to open up said section. At the lower or inner side of said hinged section 14 at opposite sides 35 of the frame are thin inwardly-projecting plates or fingers 30 (shown clearly in Figs. 4 and 8) and adapted to extend between the negative and the opposite edges of the sensitive paper to draw the latter away from said negative. When the hinged section is open, the 40 said paper being held to the negative by one section and at the opposite end of the frame to the hinged section 14 by said fingers or plates 30 when said hinged section is open. 45 The sectional back plate 35 is clamped at one end against the negative by the spring-clamp 36, having opposite-extending arms 37, adapted to engage the spring-catches 38, attached to the opposite sides of the frame-body. 50 Said sectional back plate 35 is jointed in line with the hinge-pins 16, and the sections 351 352 thereof are beveled in correspondence with the bevels 13 15, so that the section 352 will freely turn with the hinged section 14, 55 attached to the frame-body. The inner side of the back plate is lined with a soft fabric 39, such as cotton-flannel, while at the opposite side crossing the flaring joint is a covering 40, of opaque fabric, adapted to prevent transmission of light-rays through said joint. At 60 the back of the section 352 is a pair of resilient pivoted arms 42, arranged flatwise upon a single pivotal screw 43. When lying together, as in Fig. 3, under usual conditions, 65 they are adapted to enter a staple 44 at the

free end of the hinged section 14. Thus the said arms are adapted to press the back-plate section 352 down firmly against the negative or paper lying between when the hinged section 14 is caught upon the body 10, as hereinbefore described, and yet the hinge action of said back-plate section and hinged frame-section 14 will be simultaneous under the power of the springs 25 when the section 14 is released from the springs 17 17. Said arms 75 42 may be employed in connection with catching projections 45 at opposite side of the frame, in which event the said arms may be turned to lie oppositely at right angles to the position of Fig. 1, their free ends entering 80 under said projections 45 to hold the section 352 of the back plate in place. Said arms 42 are preferably seated on a transverse metallic plate 45, having raised bearings 47 at opposite ends closely adjacent to the projections 85 45, which tend to hold the free ends more positively and firmly in place beneath said projections.

In practicing the invention I first remove the back plate 35, preferably by pressing the 90 catches 38 38 outward and withdrawing the tongues 42 from the staple 44. I then press the wedge-bar 21, throw the catching-springs 17 17 outward, and permit the hinged section 14 to fly open to insert the negative on the 95 seat 17, said negative thus lying between its seat and the stay projections or fingers 30. I then close the said hinged section 14, so that the paper-retaining projections or fingers 30 are brought down on the negative at opposite 100 sides thereof, the hinged sections 14 catching automatically when pressed in closing. I then spread the paper over the negative and the retaining projections or fingers 30, reinsert the back plate, and subject the paper to 105 light-rays, as heretofore. When the printing is to be examined, the operator presses on the wedge-rod 21 to release section 14, when the latter flies open, carrying the paper with it, and exposes the sensitive side of said paper. 110 If not sufficiently exposed, the section 14 is again closed and automatically fastened by the springs 17, and this may be repeated as often as necessary, the operations being convenient and conducing to an economy of time 115 and labor.

Having thus described the invention, what I claim as new is—

1. The combination of the frame-body having a seat for a negative, a spring-catch for a hinged section and catches for a back plate, of said hinged section having a retaining projection or finger for the sensitive paper, and a sectional back plate, substantially as described. 120

2. The combination with the frame-body having a seat for a negative and catches for a hinged section, and a back plate, of said hinged section joined to said body, said back plate formed in sections, one hinged to the 130

other in line with the hinge center of said hinged section, substantially as set forth.

3. The combination with the frame-body having a seat for a negative and catches, a hinged section and a back plate, of said section hinged to said body, a spring for automatically opening said hinged section and a catch for holding the same closed, and said back plate formed in sections, one hinged to the other in line with the hinge center of said hinged section, substantially as set forth.

4. The combination with the frame-body having a seat for a negative and catches, a hinged section and a back plate, of a said section hinged to said body, and said back plate formed in sections, one hinged to the other in line with the hinge center of said hinged section, and catches for each section of said back plate, one engaging the body and the other the hinged section of the frame, substantially as set forth.

5. The combination with the frame-body having a seat for a negative, and at one end having a transverse slot in which a wedge-rod is arranged, of springs at opposite sides of said body adapted to fasten a hinged section and pins to engage the said wedge-rod, the said springs being thrown by said wedge-rod out from catching relation with said hinged section, said hinged section in connection with said frame-body, a sectional back plate, and means for securing said back plate in the frame.

6. The combination with the frame-body having a seat for a negative, and at one end having a transverse slot in which a wedge-rod is arranged, of springs at opposite sides of said body adapted to fasten a hinged section, and to be forced by said wedge-rod out from catching relation with said hinged section, said hinged section in connection with said frame-body, a sectional back plate, and fastening-springs attached to each section of the back plate, one of said sections having a pair of springs arranged on a single pivot, and adapted to be turned to lie in a given line in plan, lengthwise of the device, the hinged section of the frame being provided with a staple to receive the free ends of said pair of springs.

50 7. The combination with the frame-body having a seat for a negative, and at one end

having a transverse slot in which a wedge-rod is arranged, of springs at opposite sides of said body adapted to fasten a hinged section, and pins to engage the said wedge-rod, the said 55 springs being thrown by said wedge-rod out from catching relation with said hinged section, said hinged section in connection with said frame-body, a sectional back plate, and fastening-spring secured to one of the sections 60 and lying in the longitudinal center line of the frame, and at its free end adapted to engage the free end of the hinged section.

8. The improved photographic - printing frame in which is combined a sectional back 65 plate and a frame inclosing said black plate and comprising a frame-body, and a hinged section having, at opposite sides near the hinges of said section retaining projections for the sensitive papers, substantially as set 70 forth.

9. The improved photographic - printing frame herein described comprising a back plate and a frame consisting of a frame-body, a hinged section, catches for holding the section closed, and retaining projections disposed near to the hinges of said section, substantially as set forth.

10. In a photographic - printing frame, a back plate in hinged sections and a frame in 80 hinged sections, one of the frame-sections having inwardly, projecting, retaining - plates adapted to enter between the negative and sensitive paper and hold the latter to one of the sections of the back plate, substantially as set 85 forth.

11. In a photographic-printing frame, the sectional back plate combined with a sectional frame, said plate and frame having coinciding hinge-joints, one of the frame-sections 90 having retaining projections adapted to extend between the negative and the printing paper or material to hold the latter to a section of the back plate.

In testimony that I claim the foregoing I 95 have hereunto set my hand this 3d day of July, 1903.

WILLIAM E. BURNETT.
